United States Patent Office

Des. 230,325
Patented Feb. 5, 1974

230,325

NURSING BOTTLE AND NIPPLE

Stephen B. Sofro, Providence, R.I., assignor to Reliance
Products Corporation, Woonsocket, R.I.

Filed Sept. 28, 1971, Ser. No. 184,645

Term of patent 14 years

Int. Cl. D24—04

U.S. Cl. D83—8 A

FIG. 5

FIG. 1 is side elevation of a nursing bottle and nipple embodying my new design;

FIG. 2 is a view similar to FIG. 1 after a 90° turn;

FIG. 3 is a top plan view thereof;

FIG. 4 is a bottom plan view thereof, and

FIG. 5 is a perspective view as seen from the front of FIG. 1.

I claim:

The ornamental design for a nursing bottle and nipple, as shown.
